US00D890846S

(12) **United States Design Patent** (10) **Patent No.:** **US D890,846 S**
(45) **Date of Patent:** **** Jul. 21, 2020**

(54) **VIDEO GAME CONTROLLER**

(71) Applicant: **Performance Designed Products LLC**,
San Diego, CA (US)

(72) Inventors: **Eric B. Fulghum**, South Pasadena, CA
(US); **Alice Sebastian Minchella Jennings**, Los Angeles, CA (US)

(73) Assignee: **Performance Designed Products LLC**,
San Diego, CA (US)

(**) Term: **15 Years**

(21) Appl. No.: **29/613,066**

(22) Filed: **Aug. 7, 2017**

(51) **LOC (12) Cl.** **21-01**

(52) **U.S. Cl.**

USPC **D21/333**

(57) **CLAIM**

The ornamental design for a video game controller, as shown
and described.

DESCRIPTION

FIG. 1 is a top perspective view of a video game controller
embodying our new design;

FIG. 2 is a bottom perspective view thereof;

FIG. 3 is a top plan view thereof;

FIG. 4 is a bottom plan view thereof;

FIG. 5 is a rear elevational view thereof;

FIG. 6 is a front elevational view thereof;

FIG. 7 is a left side elevational view thereof; and,

FIG. 8 is a right side elevational view thereof.

The broken lines illustrate portions of the video game
controller that form no part of the claimed design.

1 Claim, 6 Drawing Sheets
